UNITED STATES PATENT OFFICE.

ROLLAND ROBBINS, OF CRAFTON, PENNSYLVANIA, ASSIGNOR TO THE SANITARY FOUNTAIN AND VENDING MACHINE COMPANY, OF PITTSBURGH, PENNSYLVANIA, A CORPORATION OF DELAWARE.

DESIGN FOR A STAND FOR VENDING-MACHINES.

42,591.

Specification for Design.

Patented June 4, 1912.

Application filed February 26, 1912. Serial No. 680,088. Term of patent 14 years.

To all whom it may concern:

Be it known that I, ROLLAND ROBBINS, a citizen of the United States, and residing at Crafton, in the county of Allegheny and State of Pennsylvania, have invented a certain new, original, and ornamental Design for a Stand for Vending-Machines, shown in the accompanying drawing, which is a view in perspective of the same.

I claim:

The ornamental design for a stand for vending machines, as shown.

ROLLAND ROBBINS.
